[57] CLAIM

The ornamental design for a bracket, as shown and described.

DESCRIPTION

FIG. 1 is a perspective view of the bracket;
FIG. 2 is a top or bottom view of the bracket as shown in FIG. 1;
FIG. 3 is a front elevational view of the bracket;
FIG. 4 is one side view of the bracket as shown in FIG. 1; and,
FIG. 5 is the opposite side view of the bracket as shown in FIG. 1 from the side shown in FIG. 4.
The broken line showing of a partial bar and openings is for illustrative purposes only and forms no part of the claimed design.
